(57) CLAIM

I claim the ornamental design for an eye wash station, as shown and described.

DESCRIPTION

FIG. 1 is a perspective view of an eye wash station, showing my new design;

FIG. 2 is a front elevation view thereof;

FIG. 3 is a rear elevation view thereof;

FIG. 4 is a left side elevation view thereof, the right side elevation view being a mirror image of the left;

FIG. 5 is a top plan view thereof; and,

FIG. 6 is a bottom plan view thereof.

The broken line disclosure is for illustrative purposes only and forms no part of the claimed design.
